US0D1088965S

(12) **United States Design Patent** (10) **Patent No.:** **US D1,088,965 S**
(45) **Date of Patent:** **** Aug. 19, 2025**

(54) **VAN**

(71) Applicants: **Hyundai Motor Company**, Seoul (KR); **Kia Corporation**, Seoul (KR)

(72) Inventor: **Yoon Jung Park**, Gyeonggi-do (KR)

(73) Assignees: **Hyundai Motor Company**, Seoul (KR); **Kia Corporation**, Seoul (KR)

(**) Term: **15 Years**

(21) Appl. No.: **29/944,320**

(22) Filed: **May 28, 2024**

(30) **Foreign Application Priority Data**

Dec. 22, 2023 (KR) 30-2023-0052743

(51) **LOC (15) Cl.** **12-08**

(52) **U.S. Cl.** ..... **USPC** **D12/93**

(58) **Field of Classification Search**

USPC D12/86, 90, 91, 92, 99, 164; D21/424, D21/433, 434, 533

CPC B62D 25/00; B62D 25/06; B62D 33/00; B62D 35/00

See application file for complete search history.
